(57) **CLAIM**

The ornamental design for a nose work toy for pets, as shown and described.

DESCRIPTION

The patent or application file contains at least one drawing executed in color. Copies of this patent or patent application publication with color drawing(s) will be provided by the Office upon request and payment of the necessary fee.

1. Nose work toys for pets

1.1 is a perspective view of a nose work toy for pets showing my new design;

1.2 is a front view thereof;

1.3 is a back view thereof;

1.4 is a top view thereof;

1.5 is a bottom view thereof;

1.6 is a left view thereof;

1.7 is a right view thereof;

1.8 is an exploded view thereof; and

1.9 is an enlarged view thereof.

The designs, which represent nose work toys for pets including dogs and cats, have pockets for doing nose work that allow pets to find snacks and feeds hidden in these pockets.
